UNITED STATES PATENT OFFICE.

HARRY C. MOORE AND CLYDE G. BUTLER, OF DAYTON, OHIO, ASSIGNORS TO THE AUTOMOTIVE MANUFACTURING COMPANY, OF DAYTON, OHIO, A CORPORATION OF OHIO.

AUXILIARY-AIR-INLET DEVICE.

1,334,549.

Specification of Letters Patent. Patented Mar. 23, 1920.

Application filed April 19, 1919. Serial No. 291,196.

To all whom it may concern:

Be it known that we, HARRY C. MOORE and CLYDE G. BUTLER, citizens of the United States, residing at Dayton, in the county of 5 Montgomery and State of Ohio, have invented certain new and useful Improvements in Auxiliary-Air-Inlet Devices, of which the following is a specification.

This invention relates to new and useful 10 improvements in auxiliary air-inlet devices for explosive engines, and more particularly to such devices for the explosive engines used in automobiles, air-planes and motor boats. The improvements relate specifically to the 15 type of air-inlet device disclosed in U. S. Patent No. 1,250,409.

The principal object of the invention is to provide in such an auxiliary air-inlet device, a movable member, preferably a screen, 20 which, in response to the velocity of the gas passing through it, will be raised thereby to actuate ball or other types of check valves of the sliding type for the purpose of admitting air, steam or other gas to the conduits 25 leading from the carbureter to the engine.

For the above purpose the invention contemplates the employment of simple, readily-operated and efficient mechanism to be fully described in the following specification and 30 particularly set forth in the subjoined claims.

Our invention is illustrated in the accompanying drawings, of which Figure 1 is a top plan view of our improved air-inlet device. 35 Fig. 2 is a bottom plan view thereof. Fig. 3 is a side view of the conical screen. Fig. 4 is a vertical sectional view of the device in position between a manifold connection and a carbureter. Fig. 5 is a plan view of one 40 of the arcuate levers hingedly mounted on the split retaining ring. Fig. 6 is a side view thereof. Fig. 7 is a perspective view of a fluted type of check valve that may be used in our device. Fig. 8 is a front end view 45 thereof. Fig. 9 is a side view of one of the retaining caps adapted to receive the valve spring. Fig. 10 is a perspective view of a check valve, substantially triangular in cross section, that may be employed in our device. 50 Fig. 11 is a front end view thereof. Fig. 12 is a perspective view of the ball valve and spring therefor which we prefer to employ in our device. Fig. 13 is a plan view of one 55 of the spring retaining caps, having a normal air hole. And Fig. 14 is a plan view of

another retaining cap having a larger air hole.

Throughout the specification and drawings, similar reference characters denote corresponding parts.

Referring to the accompanying drawings, the numeral 1 designates a flat, and substantially elliptical, member containing a wide elongated slot 2 in each end thereof to enable it to be firmly secured between a manifold connection 3 and a carbureter 4.

Provided in the flat member 1 is a central opening of substantially the same diameter as that of the bore of the manifold connection 3, to receive an apertured member 5. 70 The latter preferably comprises a screen of fine mesh that is conical in shape and whose marginal edges are bound by a ring 6 having a rounded top and flat bottom. (See Fig. 3.)

The flat member 1 has a slightly counter-sunk portion around its central opening to receive a retaining band 7 that forms an annular flange upon which the ring 6 of the screen 5 normally rests.

Provided in the lower portion of the flat 80 member 1 that surrounds its central opening, is an annular recess or groove that receives a split ring 8 which is adapted hingedly to secure, within that opening, the following described arcuate levers that operate the 85 check valves to admit air when the screen is raised by the velocity of the fuel passing therethrough.

Referring to Figs. 1, 4, 5 and 6, the numeral 9 designates each of these arcuate 90 levers, which are preferably four in number. Each lever 9 has extending rearwardly from each end thereof, a leg 10 terminating in an eye portion that receives the ring 8. The latter, therefore, when seated within the annular recess that receives it in the member 1, will hingedly secure the arcuate levers 9 within the central opening in the latter, above the ring 6 of the screen 5. In other words, these levers will be held by the ring 8, 100 in a position to be engaged and raised by the ring 6 of the screen when the latter is elevated by the velocity of the fuel passing therethrough. When these levers are raised by the ring 6, their outer peripheries will 105 be forced against the wall of the central opening in the member 1 to prevent the passage of fuel that might seek to go around, rather than through, the screen 5 when the latter is raised.

The primary function of the levers 9 will now be described. Provided in the flat member 1, and extending from its outer surface to the central opening within it, are radial 5 holes 11, each hole being of smaller diameter at its inner than at its outer end, to provide a shoulder or seat 12 that is adapted to be engaged by a ball valve 13 normally pressed against it by a coil spring 14. The outer 10 end of the latter seats against the interior portion of the dome 15 of a cap 16 that is secured to the marginal edge of the flat member 1 over its respective hole 11, by screws 17. The dome 15 of each cap 16 is of conical 15 shape to enable the spring 14 to accommodate itself to it as a seat, since the hole receiving said spring is oblique to said cap.

Preferably provided in the middle of the dome 15 of each cap 16 is an air-inlet hole 20 18. The caps 16 are interchangeable, so that one whose dome 15 contains a large hole to admit more air, as shown in Fig. 14, may be substituted for the one shown in Fig. 13, which contains a smaller hole.

25 The springs 14 normally hold their respective valves 13 against their seats 12, to prevent the admission of auxiliary air when the engine is running at slow speed. As is well known in the art, when the speed of the 30 engine increases, auxiliary air should be admitted in a quantity proportionate to that speed, for mixture with the fuel that ascends from the carbureter to the manifold. This fuel must pass through the conical 35 screen 5, and as its velocity increases, the screen will be raised thereby to open the valves 13 by the following means:

Extending rearwardly from the middle 40 portion of each arcuate lever 9, between and at approximately right angles to the legs 10, is a projection 19 adapted to engage a respective ball valve 13. Provided in the periphery of the flat member 1 around its central opening, one on each side of the inner end of a hole 11, is a vertical groove 20, adapted to receive and guide the lever legs 10 during their up and down movement when the screen is raised and lowered.

Each arcuate lever 9 is so hinged as to 50 permit its ends to be first engaged by the ring 6 on the rising movement of the screen. Accordingly, a great leverage of approximately three to one will be provided, to permit the projection 19 on each lever 9 sufficient force to overcome the tension of the 55 springs 14, and thrust the ball valves 13 a sufficient distance behind their seats to admit air in the proper quantity for mixture with the ascending fuel. As the speed of 60 the engine increases, the conical screen 5 will be further raised by the increased velocity of the fuel passing therethrough, with the result that the balls 13 will be pressed farther from their seats by the projections 65 19 on the levers 9 that are elevated by the

ring 6 on the screen. And, as stated before, the fuel cannot ascend around the marginal edges of the screen, but must go through it to perform its lifting function, since the outer peripheries of the levers are pressed 70 against the wall of the central aperture of the member 1, to form a barrier against the marginal ascension of the gas. Now, when the speed of the engine decreases, the screen and levers will descend by gravity, while the 75 balls 13 will be forced against their seats to prevent the further admission of auxiliary air, by the coil springs 14. Not only will the screen, in response to the velocity of the ascending fuel, perform the air admitting 80 function just described, but it will effectively resist backfire in the carbureter when too lean a mixture has gone into the cylinders of the engine.

85 The arcuate levers 9 which we provide, are multiplying in a sense, since their ends only are initially engaged by the ring 6 to provide sufficient leverage to break the vacuum when the screen 5 starts to rise. The ring 6 is not only provided to slidingly engage the levers, but to reinforce the screen and prevent it from frazzling out.

We do not wish to be limited to the ball 95 type of check valves shown and described, since other types of such valves may be employed without departing from the spirit of our invention. In Fig. 7 we have illustrated a slide valve 21 which has a fluted periphery, or one which is star-shaped in cross section, to break up into small shafts, the incoming air, rather than have it enter the manifold connection in the form of a tube. For the purpose of breaking up this auxiliary air, we have shown a slide valve 22 in 100 Figs. 9 and 10, that is approximately triangular in cross section. Both the valves 21 and 22 have an outwardly flaring outer end to rest firmly against a seat provided for it in each radial hole 11 when this type of valve is used.

We do not wish to be limited to the details of construction and arrangement herein shown and described, and any changes or modifications may be made therein within the scope of the subjoined claims.

Having described our invention, we claim:

1. In a device of the type described, the combination with a member adapted to be interposed between a carbureter and a manifold connection for an explosive engine, check valves slidable in said member for admitting air to said manifold connection, a screen loosely mounted in an opening in said member, and adapted to be moved by the velocity of the fuel passing therethrough 120 from the carbureter into said manifold connection, and lever mechanism one portion of which is adapted to be engaged by said screen and the other portion of which is adapted to engage and thrust open said 125 130

check valves, whereby, when said apertured element is actuated in response to the velocity of fuel passing therethrough, said check valves will be thrust open to admit air 5 to said manifold connection.

2. In a device of the type described, the combination with a member adapted to be interposed between a carbureter and a manifold connection for an explosive engine, 10 check valves slideable in said member for admitting air to said manifold connection, a screen loosely mounted in an opening in said member, and adapted to be moved by the velocity of the fuel passing therethrough 15 from the carbureter into said manifold connection, and arcuate levers hingedly secured in said member, adapted to be actuated by the movable screen, to engage and thrust open said check valves to admit air to said 20 manifold connection, when said screen is moved by the velocity of the fuel passing therethrough.

3. In a device of the type described, the combination with a member adapted to be 25 interposed between a carbureter and a manifold connection for an explosive engine, check valves slideable in said member for admitting air to said manifold connection, a screen loosely mounted in an opening in 30 said member, and adapted to be moved by the velocity of the fuel passing therethrough from the carbureter into said manifold connection, arcuate levers disposed around the peripheral rim of said screen, a projection 35 on each lever adapted to engage and thrust open a corresponding check valve, and means hingedly securing said levers to said member, the two ends only of each lever adapted to be initially engaged by the movable screen 40 to provide the necessary leverage to thrust open its respective check valve when the screen is actuated in response to the velocity of fuel passing therethrough.

4. In a device of the type described, the 45 combination with a member adapted to be interposed between a carbureter and a manifold connection for an explosive engine, check valves slideable in said member for admitting air to said manifold connection, a 50 screen loosely mounted in an opening in said member, and adapted to be moved by the velocity of the fuel passing therethrough from the carbureter into said manifold connection, arcuate levers disposed around the 55 peripheral rim of said screen, a projection on each lever adapted to engage and thrust open a respective check valve, a split ring seated in an annular recess provided in the wall of said member around the opening 60 therein, and a pair of eyelet projections on each lever through which said ring is adapted to pass, for the purpose of hingedly securing each lever to said member, whereby, when said levers are actuated by the movable 65 screen, they will engage and thrust

open said check valves, to admit air to said manifold connection.

5. In a device of the type described, the combination with a member adapted to be interposed between a carbureter and a manifold connection for an explosive engine, check valves slideable in said member for admitting air to said manifold connection, a screen loosely mounted in an opening in said member, and adapted to be moved by 70 the velocity of the fuel passing therethrough from the carbureter into said manifold connection, arcuate levers disposed around the peripheral rim of said screen, a projection on each lever adapted to engage and thrust 75 open a respective check valve, a split ring seated in an annular recess provided in the wall of said member around the opening therein, a pair of legs on each lever, one leg on each side of, and at right angles to, the 80 aforesaid lever projection, each leg terminating in an eye through which said ring passes to hingedly secure said levers to said member, and recesses provided in the latter at right angles to the annular recess to receive 85 the eyelet ends of said legs, to guide said levers during their valve opening movement in response to the movement of said screen.

6. In a device of the type described, the combination with a member adapted to be 90 interposed between a carbureter and a manifold connection for an explosive engine, said member provided with a central opening to which radial holes extend from the outer periphery of said member, a ball valve in 95 each hole, a seat for said valve provided in the forward portion of said hole, a screen loosely mounted in the central opening in said member, and adapted to be moved by the velocity of the fuel passing therethrough 100 from the carbureter to said manifold connection, an apertured cap affixed to said member over the outer end of each radial hole, a spring interposed between said cap and ball valve in its respective radial hole, normally 110 to hold said valve against its seat, and lever mechanism one portion of which is adapted to be engaged by said screen and the other portion of which is adapted to engage and thrust the said ball valves behind their seats, 115 whereby, when said screen is actuated in response to the velocity of the fuel passing therethrough, auxiliary air will be admitted to said manifold connection through said radial holes.

7. In a device of the type described, the combination with a flat member adapted to be interposed between a carbureter and a manifold connection for an explosive engine, said member provided with a central opening to which radial holes extend from the outer periphery of said member, a check valve in each hole, a seat for said valve provided in the forward portion of said hole, a screen loosely mounted in the central open- 120 125 130

ing in said member, and adapted to be moved by the velocity of the fuel passing therethrough, from the carbureter to said manifold connection, lever mechanism one portion of which is adapted to be engaged by said screen and the other portion of which is adapted to engage and thrust said valves behind their seats when said screen is moved by said fuel velocity, a coil spring normally holding said valves against their seats, a cap removably secured to said member around each radial hole, and an apertured conical dome for each cap, that forms a seat to which each spring readily accommodates itself and admits air to its respective radial hole.

8. In a device of the type described, the combination with a flat member adapted to be interposed between a carbureter and a manifold connection for an explosive engine, slide valves in said member for admitting

air to said manifold connection, a screen for said central opening, adapted to be moved by the velocity of the fuel passing therethrough from the carbureter to said manifold connection, a flange disposed around the bottom portion of said central opening, a binder ring around the marginal edges of said screen, normally supported by said flange, and means adapted to be engaged by said binder ring, for moving said slide valves to admit air to the manifold connection when said binder ring is raised above the flange by the screen in response to the velocity of the fuel passing through the latter. 25 30 35

In testimony whereof we have hereunto set our hands this 17th day of April, 1919.

HARRY C. MOORE.
CLYDE G. BUTLER.
